UNITED STATES PATENT OFFICE.

JOHN B. VAN DOREN, OF PROVIDENCE, RHODE ISLAND.

PYROTECHNIC DISPLAY DEVICE.

Application filed November 6, 1922. Serial No. 599,216.

To all whom it may concern:

Be it known that I, JOHN B. VAN DOREN, a citizen of the United States, and resident of Providence, county of Providence, and 5 State of Rhode Island, have invented an Improvement in Pyrotechnic Display Devices, of which the following description, in connection with the accompanying drawing, is a specification, like characters on the 10 drawing representing like parts.

This invention relates to an article for producing a pyrotechnic display.

The object of the invention is to provide a device of this character which shall give 15 a pleasing effect when set off either in the day time or at night, which shall produce at the same time a plurality of different pyrotechnic displays and which may be economically and rapidly manufactured so as to 20 be sold at a comparatively small price.

The invention further and more specifically has for its object to provide a simple form of pyrotechnic device which shall simultaneously burn sparkler composition 25 and one or more compositions producing fires of one or more colors.

These and other objects and features of the invention will appear more fully from the accompanying description and drawings 30 and will be particularly pointed out in the claims.

In the drawing;

Fig. 1 is a perspective view of one form of device embodying the invention;

35 Fig. 2 is a perspective view of another and preferred form of device embodying the invention;

Fig. 3 is a perspective view of the same device shown in Fig. 2 looking at the opposite face thereof.

40 Fig. 4 is a view in transverse cross section of the device shown in Fig. 1;

Fig. 5 is a view in transverse cross section of the device shown in Figs. 2 and 3;

45 Fig. 6 is a view in transverse section of another form of device embodying the invention somewhat similar to that shown in Fig. 1;

Fig. 7 is a view of still another form of 50 device embodying the invention and somewhat similar to that shown in Figs. 2 and 3.

The device embodies a suitable metal holder preferably of thin sheet metal such as that employed in making ordinary tin- 55 ware.

This holder is formed to present or is pro-

vided with means to retain adherent thereto an elongated body of a suitable pyrotechnic composition such as sparkler composition and also to present a suitable handle portion. 60 This result is preferably secured as illustrated in the drawings by forming the thin sheet metal at one end into cylindrical form of sufficient length to serve as a handle by which the device may be held and by forming the other end with an elongated groove.

In the device shown in Figs. 1 and 4 the latter end of the holder is formed to present a V-shaped groove 2 extending throughout its length. In the preferred form of the device shown in Figs. 2, 3 and 5 the latter end of the holder is formed to present an elongated groove having a flat bottom surface 3 and inclined sides 4 and in addition flanges 5 extending laterally at the top of the inclined sides 4. In Fig. 7 which illustrates the cross section of another form of holder the elongated groove 6 is V-shaped as in Fig. 1 and wide flanges 7 are provided extending laterally from the top of the inclined sides of the groove. There are thus illustrated various forms which the device may take and other forms may be provided within the scope of the invention as defined in the claims.

The groove in either form of the device is filled with an elongated continuous body of a suitable pyrotechnic composition and for that purpose there is preferably employed the so-called sparkler composition which is ordinarily composed of barium nitrate, powdered aluminum, powdered iron and dextre sizing. This composition when ignited burns slowly with a brilliant sparkling effect. This composition is preferably applied first because it is a water mixed composition and must be dry before compositions mixed with alcohol are added to the holder. This sparkler composition is held in place by adhering to the walls of the groove.

In the form of device shown in Fig. 1 after the body of sparkler composition 8 is in place in the groove 2 of the holder there is added in localized bodies or spots one or more different colored pyrotechnic compositions. As illustrated these spots or bodies of composition are placed directly on top of the sparkler composition 8. As illustrated the spots 9 may be of the ordinary red fire pyrotechnic composition and the spots 10 of the ordinary blue fire pyrotechnic composition. Such red fire, blue fire and other simi-

lar pyrotechnic compositions are alcohol mixtures and are, therefore, preferably applied after the sparkler composition has dried.

- 5 To set off the device the extreme end is ignited and then the sparkler composition burns emitting the dry sparks which characterize this composition. As it burns and the spots or bodies of red fire, blue fire or other 10 pyrotechnic composition are reached they are ignited and burned thus giving off at the same time the different colors along with the display of the sparkler composition. It is thus possible to have red, white and blue 15 effects. Other compositions such as the so-called red meteor pyrotechnic composition composed of red fire composition and powdered aluminum make effective additions to the device.
- 20 In the preferred form of the device shown in Figs. 2, 3 and 4 the sparkler composition is applied in the same manner as before filling the groove 3 but the spots 12 and 13 of the various colored pyrotechnic compositions 25 are applied on the opposite face of the holder and preferably along the flat surface 14. These spots or localized bodies of pyrotechnic composition are adherent to the sheet metal of the holder and are readily ignited 30 by the heat conducted from the burning sparkler composition through the metal holder. This arrangement keeps the colored pyrotechnic compositions entirely separate from the sparkler composition and insures 35 the burning of each separately and the maintenance at the same time of the characteristic display of the different compositions.
- If desired as indicated in the cross section shown in Fig. 6 the device may be made in 40 the form shown in Fig. 1 with the colored pyrotechnic composition as for example the red fire composition 15 arranged in spots or as a continuous body along one of the back faces of the holder and another composition 45 such as a blue fire composition 16 similarly arranged in spots or as a continuous body along the other inclined face. Still another arrangement is illustrated in Fig. 7 where the construction of a holder is similar to that 50 shown in Fig. 3 but with the flanges 7 of greater width. In this case the colored pyrotechnic composition such as the red fire composition 17 and the blue fire composition 18 may be arranged in spots or as continuous 55 bodies along the face of these flanges. The article produced by the invention is readily

and cheaply made and provides a very brilliant and spectacular pyrotechnic display and is particularly suitable for celebration of Fourth of July and other holidays by 60 children and others.

Having thus described my invention, what I claim as new, and desire to secure by Letters Patent, is:

1. A pyrotechnic display device comprising a long narrow longitudinally grooved sheet metal holder, a continuous body of pyrotechnic composition in the groove and adherent to the holder, and a plurality of localized bodies of pyrotechnic composition 65 adherent to the holder on the face opposite the groove and successively ignitable by the heat conducted through the metal of the holder from the burning composition in the groove. 70
2. A pyrotechnic display device comprising a long narrow longitudinally grooved sheet metal holder, a continuous body of pyrotechnic sparkler composition in the groove and adherent to the holder, and a plurality 75 of localized bodies of different colored pyrotechnic composition adherent to the holder on the face opposite the groove and successively ignitable by the heat conducted through the metal of the holder from the burning sparkler composition in the groove. 80
3. A pyrotechnic display device comprising an elongated grooved metal holder, a continuous body of pyrotechnic composition in the groove and adherent to the holder, and localized bodies of pyrotechnic composition different from that in the groove associated with the holder and ignitable from the burning composition in the groove. 85
4. A pyrotechnic display article comprising a long narrow longitudinally grooved sheet metal holder and a continuous body of pyrotechnic composition located in the groove and adherent to the holder. 90
5. A pyrotechnic display device comprising a long narrow longitudinally grooved sheet metal holder, a continuous body of pyrotechnic composition in the groove and adherent to the holder and localized bodies of different pyrotechnic compositions separated 95 from each other, adherent to the holder and in positions to be ignited by the heat generated by the burning composition in the groove. 100

In testimony whereof, I have signed my name to this specification.

JOHN B. VAN DOREN
